UNITED STATES PATENT OFFICE.

HENRY CRUSE, OF MANCHESTER, ENGLAND.

STEAM GENERATOR AND SUPERHEATER.

SPECIFICATION forming part of Letters Patent No. 638,006, dated November 28, 1899.

Application filed October 1, 1898. Serial No. 692,435. (No model.)

To all whom it may concern:

Be it known that I, HENRY CRUSE, engineer, a subject of the Queen of Great Britain, residing at Blakeley, in the city of Manchester, 5 England, have invented a new and useful Apparatus for and Method of Superheating Steam in Generating the Same in Connection with Steam-Boilers, (for which I have applied for a patent with provisional specification in 10 Great Britain, No. 5,103, bearing date March 2, 1898,) of which the following is a specification.

My invention relates to improvements in the method of and apparatus for generating 15 steam, and has chiefly for its object to economically produce dry superheated steam or steam gas adjusted in temperature to the requirements of the work.

The invention is applicable to Lancashire, 20 Cornish, Marine, Babcock, and other types of tubular or semitubular steam-boilers by modifications of design of the apparatus to suit each case. To accomplish this and to effect 25 my improvements, I provide means for a method of generating steam in connection with a steam-boiler, consisting of a series of wide-bore pipes suitably connected and forming a superheating apparatus, which is placed in the inner or outer flue or in the uptake or 30 downtake of the boiler or boilers or otherwise, according to the type of boiler employed, or it may be independently heated or fired. Inside these superheater-tubes other and 35 smaller tubes or pipes are placed, through which the water flows, and the inner or water tubes or pipes are thereby surrounded or jacketed by the superheated steam or steam in process of being superheated by the action 40 of the hot gases from the boiler furnace or furnaces or other source of heat. By this means a system of circulation may be provided for the water of the boiler, in that the water flowing through the water-tubes inside 45 the superheater can be taken or conducted from the lower part of the boiler at any convenient point and returned thereto in the steam or upper water space with a greatly-increased temperature, the conversion from water to steam being thereby greatly facilitated.

50 When required, however, I may pass the feed-water through this inner system of water-pipes within the superheater or in alternation.

It will be seen from the foregoing that I prefer the water to travel in the same direction as the steam through the various pipes 55 of the superheater, and that the heat given to the steam by the surrounding gases from the furnace is in turn given off to the water in the internal tubes, and that as the water proceeds in its course it approximates more 60 and more to the heat of the steam. To enable this approximation to be adjusted or maintained at the desired degree, I may arrange to connect the feed-water pipe at any convenient point or points in the run of the super- 65 heater apparatus, and suitable valves and connections may be employed to enable either the feed-water or the water from the boiler to be separately cut off from the superheater.

Although I prefer the form of the super- 70 heater, together with the internal water-tubes, to be circular in cross-section, oval or other cross-sectional design may be employed in the construction of my apparatus and other variations in detail may be made in the general form, dimensions, and position of the superheating and generating apparatus and in the character and number of the various sections and in the arrangement of the requisite valves for directing the water in the 75 inner tubes and for directing the superheated steam either back into the boiler or directly to the work required of it without departing from the peculiar character of the invention.

That the invention may be the better understood I will, with the aid of the accompanying drawings, proceed to describe its application to one type of boiler—to wit, the Lancashire boiler.

In the drawings, Figure 1 represents a longitudinal section of a Lancashire boiler fitted with my invention, and Fig. 2 shows a plan view and sectional plan thereof, while Fig. 3 represents a sectional elevation of the apparatus at the back end of the boiler; and Fig. 4 shows an enlarged section, and Fig. 5 an enlarged plan, of certain details for joining up the apparatus in series.

The same letters indicate corresponding 100 parts wherever they occur.

The steam to be superheated is taken from any convenient point within the boiler—as, say, at I—by employing an antipriming col-

lector, whence it passes through the bend C' into the first superheater-tube A. It then travels down this tube through the bottom box B, up the tube A', and in like manner 5 through the whole series of superheaters, emerging by three-way pipe E at top of tube A⁵, and then proceeds, by pipe F and stop-valve F', to main steam-pipe H. The water is tapped at blow-off tube R, passing through 10 stop-cock R' and mud-catcher R² for convenience and thence by pipe P to the superheater, which it enters by three-way pipe D, situated in the case shown just below the steam-inlet valve C. From this point the 15 water flows within the inner tubing of the apparatus until the required length of the superheater having been traversed the water leaves the same by the three-way pipe E and enters the steam-space of the boiler at any 20 convenient point--as, say, through the back plate--and may be carried by pipe a suitable distance inside the boiler, as may be desired and is well understood, or the water may pass from three-way pipe E by pipe to front of the 25 boiler and enter by the feed-inlet. At suitable points stop-cocks, such as M, M', and M², are fixed in circuit and through all or any one of these the feed-water supply to the boiler is connected from the branch pipe S 30 with the boiler-water in the internal tubing N. It will thus be seen that the essential feature of my invention consists in forming a jacket of steam to the water-tubes contained therein, whereby I obtain a superheater which, on the 35 one hand, is controllable by the water passing through it, while, on the other hand, I am enabled to heat the feed-water passing through superheater or superheat the water from the boiler for circulatory purposes at will. 40 The enlarged views, Figs. 4 and 5, show the means I employ to form the top cap for join-

ing together individual superheating and internal water-tubes and for making the various water-tube connections in series, and which arrangement constitutes an important and 45 special detail of my invention. In all types of boilers or steam-generators resembling the Lancashire boiler I prefer thus to join up the members of my superheater apparatus in series and arrange the same as illustrated; but 50 there are types of tubular boilers wherein it may be more convenient to arrange isolated individual members, forming separate superheaters, each of which may communicate with the water-space and steam-space, as will be 55 readily understood, for which purpose the tubes may be curved, if desired.

I am aware that superheaters of various forms have already been employed, and feed and circulatory water has been heated in 60 pipes by having superheated steam passing through the water-pipes by means of internal steam-tubes; but these are entirely different to and, indeed, the reverse of my method and apparatus, and I lay no claim thereto; but 65

What I do claim as my invention, and desire to secure by Letters Patent, is—

In a steam-generating device, the combination of a superheater-chamber situated in the furnace-flue, with the circulating water-pipe 70 connected above and below to the boiler and passing through said superheater, and a steam-pipe connecting the superheater with the steam-space of the boiler, substantially as described.

In witness whereof I have hereunto set my hand in presence of two witnesses.

HENRY CRUSE.
